UNITED STATES PATENT OFFICE.

WILLIAM H. BUELL, OF NEW HAVEN, CONNECTICUT.

PRIMING CHARGE.

1,312,156.

Specification of Letters Patent.

Patented Aug. 5, 1919.

No Drawing

Application filed July 21, 1916. Serial No. 110,493.

To all whom it may concern:

Be it known that I, WILLIAM H. BUELL, a citizen of the United States, residing at New Haven, in the county of New Haven, State 5 of Connecticut, have invented a new and useful Improvement in Priming Charges; and I do hereby declare the following to be a full, clear, and exact description thereof.

My invention relates to a priming charge 10 for use in igniting explosives, which is of especial utility in igniting the various smokeless and black powders when used in center fire and rim fire ammunition.

The purpose of my invention is to produce 15 a priming charge which is particularly suited for use with powders as now employed in fire arms, and particularly small arms, such charge producing an explosion of not too great local pressure, and of sufficient heat, and leaving substantially no harmful residues; in its specific form, my invention contemplates the modification of 20 the flash of the priming charge, giving it greater length, and the additional advantage that, unlike fulminate of mercury, which is commonly used in primers, there can be no amalgamation with resultant deterioration of the metal of the primer cup or shell cartridge.

According to my invention I produce a priming charge by mixing, intimately, a detonating salt of trinitroresorcinol with a suitable nitrated organic body. For instance, I may mix four parts by weight of 25 normal lead trinitroresorcinate with one part by weight of nitrocellulose and mix the same to produce a substantially homogeneous product. The mixture above described will be found suitable for use alone 30 in small arms ammunition, the local pressure of the explosion being reduced and its heat increased. Substantially, no residue is left which may injure the shell or bore of the firearm. While I prefer to use the normal lead salt I may use other suitable salts 35 of trinitroresorcinol, for instance, the barium salt.

In place of nitrocellulose I may employ some other suitable nitrated organic body, 40 such as for instance, one of the aromatic nitro-compounds as trinitrotoluol or dinitrobenzene; the aliphatic nitro-compounds, such as tetranitromethane. While the proportions most suitable for the mixture may

differ with various substances and also with 55 various powders in connection with which the mixture is to be used, they are easily determined by anyone skilled in the art. I desire it to be understood that it is possible that some nitrated organic bodies in combination with a detonating salt of trinitroresorcinol may not produce a primer having the explosive qualities above described and that I therefore include in my invention the use of such bodies only as will in 60 65 such combination produce such a primer.

It is also to be understood that the term, detonating salt of trinitroresorcinol, refers to such salts of trinitroresorcinol as will detonate and are suitable for use as a 70 primer.

I may also add other substances to my priming mixture, thus, chlorate of potash or some other oxidizing compound, as the perchlorates, nitrates, and peroxids of 75 barium, potassium, sodium, etc., may be added to the mixture or in part substituted for certain ingredients or I may add an inert substance such as powdered glass for the purpose of making the mixture more 80 sensitive.

I may, for instance, mix fifty parts, by weight, of normal lead trinitroresorcinate and twelve parts, by weight, of nitrocellulose and eighteen parts, by weight, of chlorate of potash with twenty parts, by weight, of ground glass. It will be found that this mixture when exploded will have all the advantages above claimed for the mixture of the normal lead salt of trinitroresorcinol 90 and nitrocellulose alone and will have the additional advantages of an increased flame. The proportions may have to be varied under different circumstances and conditions and with different materials and with different powders, but they can readily be ascertained by anyone skilled in the art.

The mixtures above specifically referred to, either of two, three or four substances, constitute a uniform mass of a bright yellow color which may be moistened with a gum solution and then introduced into the primer cup, where it is seated under heavy pressure and may then, if desired, be covered with paper or foil or by a thin film of 100 105 collodion or gum. An anvil of any suitable construction may then be inserted into the cups. When the primer is to be used in

rim fire ammunition, it is preferably given the treatment with the gum solution and then driven into the annular rim of the cartridge shell by centrifugal force. It may 5 then be covered with collodion.

The priming mixtures described in the above specific examples are homogeneous in character and of the proper igniting qualities so that a hot and uniform flame is produced without an excess of normal pressure and with a minimum of harmful residue or none at all. The flame produced has the proper velocity and intensity to ignite the powder charge before imparting any 10 appreciable motion to it before ignition and thus effects an explosion having the maximum pressure near the breech of the gun and not one which is delayed until the charge is near the muzzle, the portion of 15 the barrel least adapted to withstand bursting pressures.

The subject matter of my invention must not be confused with detonators nor with priming charges which are not suitable for 20 use in fire arms. To make a priming charge suitable for use in fire arms, it must not be too violent in action, but must, on the other hand, be capable of being exploded by the action of the firing pin or other firing mechanism striking against the casing which 25 contains the charge.

When I speak in my claims of a priming charge I refer to an initial priming charge and not one that must either be ignited by 30 another, separate, initial priming charge, or have admixed therewith a more sensitive substance than the salt of trinitroresorcinol referred to therein.

I claim:

40 1. A priming charge containing a mixture of a detonating salt of trinitroresor-

cinol and a nitrated organic body, substantially as and for the purpose described.

2. A priming charge containing a mixture of a detonating salt of trinitroresorcinol and nitrocellulose, substantially as and for the purpose described.

3. A priming charge containing a mixture of normal lead trinitroresorcinate and a nitrated organic body, substantially as and for the purpose described.

4. A priming charge containing a mixture of normal lead trinitroresorcinate and nitrocellulose, substantially as and for the purpose described.

5. A priming charge containing a mixture of detonating salt of trinitroresorcinol, a nitrated organic body and an oxidizing compound, substantially as and for the purpose described.

6. A priming charge containing a mixture of a detonating salt of trinitroresorcinol, nitrocellulose and an oxidizing compound, substantially as and for the purpose described.

7. A priming charge containing a mixture of normal lead trinitroresorcinate, a nitrated organic body and an oxidizing compound, substantially as and for the purpose described.

8. A priming charge containing a mixture of normal lead trinitroresorcinate, nitrocellulose and an oxidizing compound, substantially as and for the purpose described.

9. A priming charge containing a mixture of normal lead trinitroresorcinate, nitrocellulose and potassium chlorate, substantially as and for the purpose described.

In testimony whereof I have hereunto set my hand.

WILLIAM H. BUELL.
